CHILD'S TEETHER

Benjamin J. Feldstein, New York, N. Y.

Application May 4, 1956, Serial No. 41,347

Term of patent 7 years

(Cl. D83—1)

FIG-1-

FIG-2-

Fig. 1 is a front elevational view of a child's teether showing my new design; and

Fig. 2 is a side elevational view thereof.

The rear of the device is substantially plain.

I claim:

The ornamental design for a child's teether, as shown and described.
